HOPPER FEED CONTROL MECHANISM FOR
SLIDE FASTENER STRINGER FORMING
APPARATUS

David Silberman, Brooklyn, N. Y., assignor to Universal Slide Fastener Co. Inc., New York, N. Y., a corporation of New York

Application February 17, 1939, Serial No. 256,914

3 Claims.

(Cl. 153—1)

This invention relates to improvements in hopper feed control mechanisms for slide fastener stringer forming machines.

Up to the present time, in machines for forming slide fasteners wherein pre-formed scoops are hopper fed to mechanisms for mounting onto the tape considerable difficulty has been encountered due to the fact that no definite control has been developed for supplying scoops in pre-determined amount and in a constant flow to the distributor for delivery to the chute and thence for mounting means. Usually, in apparatus of this type, an operator feeds an undetermined amount of scoops into the distributor at random and, as a result of this practice, either overloading or underloading of the distributor occurs, in the case of the former causing a jamming at the chute entrance and in the latter in the midst of operations providing unwanted gaps in the stringers being formed, due to failure of delivery of scoops into the chute.

To obviate this difficulty, I have provided a hopper feed control assembly which may be associated with any of the various types of apparatus applying pre-formed scoops to the tape for forming stringers, wherein there is delivered periodically from a hopper to the distributor a pre-determined number of scoops sufficient to at all times maintain the necessary level of scoops in the distributor for delivery into the chute.

Specifically, it is an object of this invention to provide a hopper feed control wherein there is synchronized for operation with the scoop mounting mechanism an ejector valve control feed mechanism for delivering to the distributor a pre-determined amount dependent upon the operation of the speed of the machine for maintaining a positive unhindered flow of scoops from the distributor to the chute.

These and other advantages, capabilities and features of the invention will appear from the subjoined detailed description of one specific embodiment thereof, illustrated in the accompanying drawings, in which—

Figure 1 is a front elevation of a slide fastener stringer forming apparatus incorporating my hopper feed control.

Figure 2 is an enlarged front elevation in section of the hopper unit.

Figure 3 is an enlarged side elevation partly in section taken along lines 3—3 of Figure 1.

Figure 4 is an enlarged front elevation in perspective of the driving portion of the hopper feed control.

Figure 5 is a side view of the ejector element of the hopper feed control.

Referring to the reference characters in the drawings, the hopper feed control shown in detail in the heavy lines of the drawings may be applied to various types of slide fastener stringer

forming apparatus and, for the purpose of illustration, is shown in association with an apparatus of the character disclosed in the patent to Nagele, 2,094,715, the assembly of which is illustrated in the fine lines of Figure 1.

Referring particularly to Figure 1, the essential elements of the stringer forming apparatus to which the hopper feed control is applied are the distributor head A, the delivery chute B, the scoop mounting mechanism C, the scoop spacing control D, and a drive shaft E controlling the same, all being carried on frame F.

The hopper feed control assembly shown generally in full lines at the right of Figure 1, comprises of a bracket 10 mounted on the frame F and supporting an upstanding tubular stem 11, at the upper end of which is carried hopper 12.

The hopper 12, as shown in detail in Figure 3, comprises a cylindrical body 13, provided with a cap 14 at its feed opening, and a substantially inverted frusto-conical base 15 at its delivery opening. At the lower end of body 13 there is mounted as by brazing thereto, a cross-rod 16, carrying a conical baffle 17 extending within the base 15. Integral with and depending from the base 15 there is formed a neck 18 having an angularly branching hollow cylindrical arm 19; the neck 18 serving as a mounting sleeve for the hopper on the stem 11, and the branching arm 19 serving as a supporting sleeve for the conduit 20 leading from inlet port 19' at the jointure of arm 19 and neck 18 to the distributor A.

In neck 18 there is formed socket 21 in which is disposed spring pressed plunger 22 carrying a knob 23 at one end and a projection 24 at the other; there being provided a circular slot in the enlarged chamber 25 defined at the upper end of the stem 11, for passage of projection 24 of the plunger 22 to latch the hopper 12 from rotary movement with respect to the stem.

Within the neck 18, which serves as a sleeve, there is mounted for reciprocation a slide valve ejector 26 shown in detail in Figure 5, the same being formed of a casting or the like provided with an open charging port 27, a base 28 and at its side a discharge port 29; the interior of the slide valve 26 being shaped to provide a curved sloping channel 30 leading from charging port 27 to discharge port 29. The wall section 31 adjacent the outlet port 29 is of length and so formed, to open or close in varying degrees the inlet port 19' between the neck 18 and the branch arm 19, in conjunction with discharge port 29.

The slide valve ejector 26 has mounted on its base a downwardly extending leg 33 and at its side an outwardly extending arm 34, the latter passing through a rectangular slot 35 of the neck. A tension spring 36 extends from arm 34 to a lug mounted exteriorly of the neck, for normally

maintaining the valve 26 in closed position, shown in Figure 3.

Within the enlarged upper section 25 of stem 11 there is mounted a plunger 37 having an upstanding projection 38 adapted to contact leg 33 of slide valve ejector 26, the plunger being mounted on driving rod 68 supported on slide block 39, the latter being mounted for reciprocation at the base of stem 11 (Figures 3 and 4).

Slide block 39 is provided with a longitudinally extending slot 40 opposite to which there is provided in the stem 11 a corresponding longitudinal slot 41 of greater extent. To the slide block there is attached exteriorly of the stem slide bar 42; the slide rod and slide block being attached to one another by means of screw 43 passing through the slide bar, the slot in the stem, and embedded in the slide block; there being provided above and below the locking screw guide elements 44, each comprising a threaded end embedded in the slide block and a head resting within apertures of the slide rod and a central bearing surface resting within the channel 40 of the slide block and slot 41 of the stem.

The lower end of the slide bar 42 is mounted within channel 46 of driver 45 and is fastened thereto by screw fastening elements 47. The lower end of driver 45 is offset and bifurcated, and carries on shaft 48 between the arms of the bifurcation, roller 49 riding on cam 50 carried on extension shaft 51 keyed to the main drive shaft E for the mounting means C and spacing control D, said extension shaft 51 being supported for rotation in bearings defined by bracket 52 and arm 54 forming an extension of bracket 10. A tension spring 55 is fastened at one end to slide rod 42 and at the other to bracket 11.

In order that the function of the elements of the hopper feed control be indicated in their correlation with the remainder of the slide fastener stringer forming mechanisms some of the details of construction of the same will be indicated. One of the feed cylinders 60 forming part of the mounting means between the threads of which scoops 61 pass from the guideway 62 of chute B for mounting on the tape is coupled by worm 64 and wheel 65 and shaft E to toothed driving wheel 66 carrying endless spacing band 67 and to this shaft, transmitting the motion from the feed cylinder to the spacing control gear there is keyed extension shaft 51 carrying control cam 50 for the hopper feed mechanism.

As the feed cylinders 60 operate to provide a mounting of scoops onto the tape, and the spacing control D acting on band 67 limits the flow of scoops to provide the spacing thereof in groups on the tape, the hopper feed control is actuated through the cam 50 to function at pre-determined intervals in the rotation of such shaft.

Following is the operation of the hopper feed control: as shaft 51 rotates, taking Figure 3 to illustrate the lowest position of the valve 26, shown in full lines, roller 49 on slide bar 45 contacting the surface of the cam 50 is gradually moved upwardly until the highest bulge 51 of the cam is attained, by which time the valve has moved to the dotted lines view shown in Figure 2, with its outlet port 29 in line with the inlet port 19 of the arm 19, by virtue of the upward movement of the slide block 39, the drive rod 68 carried thereby, plunger 37 and upstanding projection 38 on such plunger acting on depending

leg 33 of the valve base, slide block 39 being displaced in the upward movement against the tension of spring 55 and the valve being moved against the tension of spring 36; as the cam 5 comes to the dwell portion which provides practically a vertical drop (see Figure 2), springs 36 and 55 respectively draw the valve 26 and the slide block 42 from their dotted line position (Figure 2) to their full line position.

Immediately the roller 49 riding on the gradually increasing diameter of the cam surface, after passing the dwell thereof, comes to gradually lift the slide block and correspondingly open the valve until the greatest radius of the cam is obtained. During this gradual opening of the valve scoops carried in the hopper and always filling the interior of the valve are gradually discharged through the outlet port of the valve as the upper end of the same passes the lower end of the cam opening until the dotted line position of the valve is attained.

The valve is so formed as regards its size and the cam is so constructed as to provide sufficient scoops for delivery into the distributor without overloading the same, nor underfeeding the same; as, for example, during the period when the mounting mechanism functions but no scoops are fed by virtue of the spacing control, the hopper feed control continues but the amount of scoops fed is determined by the size of the valve interior and the outlet port provides for sufficient feed of scoops to maintain a continuous flow from the distributor to the chute.

It is obvious that various changes and modifications may be made to the details of construction without departing from the general spirit of the invention as set forth in the appended claims.

I claim:

1. In a slide fastener stringer forming apparatus, in combination with a distributor continuously feeding pre-formed scoops for mounting onto a tape, a charging device for said distributor comprising a hopper carrying pre-formed scoops, a passageway between the hopper and distributor, a control valve reciprocable in said passageway, and means periodically actuating said valve for delivering of scoops in pre-determined amounts from said hopper to said distributor.

2. In a slide fastener stringer forming apparatus, in combination with a distributor continuously feeding pre-formed scoops for mounting onto a tape, a charging device for said distributor comprising a hopper carrying pre-formed scoops, a passageway between the hopper and distributor, a control valve reciprocable in said passageway providing and closing communication between said hopper and distributor, and means actuating said valve for permitting periodic delivery of scoops in pre-determined amounts from said hopper to said distributor.

3. In a slide fastener stringer forming apparatus, in combination with a distributor continuously feeding pre-formed scoops for mounting onto a tape, a charging device for said distributor comprising a hopper carrying pre-formed scoops, a passageway between said hopper and distributor, a valve in said passageway incorporating a measuring chamber and reciprocable in said passageway for charging and discharging, and means actuating said valve for permitting periodic discharge of scoops in pre-determined amounts from said hopper to said distributor.

DAVID SILBERMAN.
